UNITED STATES PATENT OFFICE.

LOUIS J. VAN GELPEN, OF CINCINNATI, OHIO.

BURNISHING-MACHINE.

1,300,059.

Specification of Letters Patent.

Patented Apr. 8, 1919.

Application filed December 6, 1915. Serial No. 65,207.

To all whom it may concern:

Be it known that I, LOUIS J. VAN GELPEN, a citizen of the United States, and a resident of the city of Cincinnati, in the 5 county of Hamilton and State of Ohio, have invented certain new and useful Improvements in Burnishing-Machines, of which the following is a specification.

The object of my invention is to produce 10 a cheap, simple, and highly efficient machine for burnishing or finishing leather articles or the like, or any other kind of material or article to be burnished or finished.

The salient features of the invention consist in providing a heated slotted finger or 15 burnishing tool which reciprocates or oscillates in connection with pressure and oscillating feeding mechanism for automatically feeding the material to be burnished and 20 thus imparting to the material a reciprocating or oscillating movement while being burnished.

The various features and advantages of 25 the invention will readily become apparent from the following specification.

In the accompanying drawing forming part of this specification:

Figure 1, represents a plan view of my machine,

30 Fig. 2, represents an end view of Fig. 1, Fig. 3, represents a side elevation, Fig. 4, represents an end view, Fig. 5, represents an enlarged view of Fig. 2, with part of the frame broken away, 35 Fig. 6 is a sectional view on line 6—6 of Fig. 1,

Fig. 7 is a sectional view of Fig. 1 with part of the frame broken away,

Fig. 8 is a sectional view on line 8—8 of 40 Fig. 1,

Fig. 9 is a sectional view on line 9—9 of Fig. 3,

Fig. 10 is an enlarged view of Fig. 1 with part of the arm broken away,

45 Fig. 11, is an enlarged view of the feeding arm and feed roller,

Fig. 12, is an end view of Fig. 11, and

Fig. 13, is an enlarged view of the internal cam.

50 My machine consists of a frame 1 provided with an upward and forward extending portion or arm 2; in the forward end of arm 2 I place vertical bearings 3 and 4, see Fig. 6. The purpose of the bearings 3 and 4, is to hold the shaft 5 in a vertical position and to allow same to slide freely. Fas-

tened to shaft 5 at its lower end, I place the downward extending arm 6. At the lower end of arm 6, I place the flat head screw 7; said screw acting as a stud or axis for feed 60 roller 8 which is also attached to said arm through medium of said screw. The feed roller 8 has a knurled or roughened surface as shown in Fig. 12. On the shaft 5 and between bearings 3 and 4, I fasten collar 9. 65 Around shaft 5 and placed between the bearing 3 and collar 9, I compress the spring 10 as shown in Fig. 5. The action of spring 10 against the rigid bearing 3 and the collar 9 on shaft 5, is to expand laterally, thus causing a downward pressure to the shaft 5 and arm 6 and consequently feed roller 8. 70

In the upward and forward extending arm 2, and at its middle, I construct bearing 12. Through bearing 12 I oscillate shaft 13 75 and at the upper end of shaft 13, I fasten collar 14. At the lower end of shaft 13, I securely fasten the housing 15. Between the housing 15 and lower end of bearing 12, I place an asbestos washer 16. Thus it can 80 be seen that the collar 14 acting as a thrust bearing against the upper face of bearing 12, will hold the housing 15 in position. The housing 15 is constructed so as to admit an electric unit 17. At the forward end of 85 housing 15, I securely fasten the burnishing tool or finger 18, projecting downward and away from the housing 15 at a suitable angle; see Fig. 6. Thus it will be seen that when the electric current is applied to unit 90 17, the heat generated by this means, will be distributed to the burnishing tool 18. In the lower end of tool 18, I place a slot 19. The slot 19 is placed laterally with the feeding mechanism, to be described later; said 95 slot may be of any desirable shape or contour.

In order to oscillate tool 18, I adopt the following means. In the upward and forward extending arm 2, I place bearings 20 100 and 21; see Fig. 10. Through these bearings the shaft 23 is revolved and held in position by means of the collars 24 and 25, which are fastened to shaft 23. The forward end of shaft 23, is turned smaller in 105 diameter and offset, thus forming an eccentric 26. Journaled on this eccentric 26, I connect the link 27, as shown in Fig. 10. The other end of link 27, is journaled on the stud 28, which is secured to housing 15, 110 at bearing 29. Thus it can readily be seen that when the shaft 23 with its eccentric end

is revolved, the housing 15 will receive an oscillating motion, through the means of the link 27 and its connections and also the finger 18, which being connected to said housing, will reciprocate with it.

The automatic feed of my machine is one of its important features for burnishing. My object is to feed the lateral edges of the material to be burnished, through the slot 19, in the burnishing tool 18, and also to reverse this feed, intermittently. To obtain this result I adopt the following means. In the frame 1, I place bearings 30 and 31, in which I oscillate the shaft 32. I also place the bearings 33 and 34 in the frame 1, in which I oscillate shaft 35, as shown in Fig. 7. Centrally placed between the two shafts 32 and 35 and journaled in the bearings 36 and 37, in frame 1, I have the main driving shaft 38. Shaft 38 is held in position by means of collars 39 and 40. Fastened on shaft 38, I have the internal cam 41. Cam 41 is a double acting cam, having the two noses 42 and 43 and a parallel race way or cam groove 44 to admit the roller 45, as shown in Fig. 8. The roller 45 is connected to the sliding arm 46 by means of a stud and must revolve freely on said stud. The sliding arm 46, has a forked shaped end 47, which slides over and under the shaft 38. The collar 63 on shaft 38 holds the sliding arm 46 in position against cam 41. At the other end of the arm 46, I connect the rocking arm 48, at the point 49. The arm 48 is fastened to shaft 32. At the forward end of shaft 32, I also fasten arm 50. At the upper end of arm 50, at the point 51, I connect the feeding arm 52. The feeding arm 52, has a fork shaped end 53, which slides over and under the roller 54. The roller 54, is fastened by means of a stud to the arm 55. Arm 55 is fastened to shaft 35 at the forward end of said shaft. The feeding arm 52, is constructed with a feeding plate 56; said plate being held in position by means of screws 57 and 58. The top of the frame 1, is cut away at the point 59, to allow the feeding plate 56, to extend up through the frame 1 and to come into contact with the face of the feed roller 8; see Fig. 12. The top face of the feed plate 56, has a knurled or roughened surface, as shown in Figs. 10 and 11.

The feed roller 8, actuated by the spring 10, has a downward pressure upon the feed plate 56 and the downward travel of the feed wheel 8, can be governed by the collar 9 on shaft 5, said collar being adjustable, to and away from bearing 4, by means of a set screw in collar 9, the said collar 9 then acting as a stop against the lower bearing 4, thus limiting the travel of feed wheel 8.

On shaft 35, I fasten arm 60 and on main shaft 38, I place the cam 61, as shown in Fig. 7. The cam 61 is constructed with one

nose 62; see Fig. 9. Connected to arm 60, at point 64, I have the sliding arm 65, with a fork shaped end, passing over and under shaft 38. The roller 66 revolving against the face of the cam 61 and held in position by means of stud 67, is fastened to the sliding arm 65. A spring 68 is connected to the forked end of arm 65 and at its other end is fastened to frame 1, at point 69, thus causing tension between said points and holding the roller 66 against the working surface of cam 61. A collar 70, holds the arm 65 in position against the cam 61, as shown in Fig. 7. Power is applied to shaft 23 through pulley 75. On shaft 23, I place spur gear 76 and on shaft 38, I place spur gear 77; the diameter of the gear 76 is one half the diameter of the gear 77, so that the shaft 23 makes two complete revolutions while the shaft 38 is making one complete revolution.

In order to get a perfect burnishing effect, the slot 19 in the burnishing tool 18 lies approximately in the plane in which the work engaging face of the feed plate 56 engages the work. The feeding mechanism, just described, must be timed as follows. The cam 41, with its double acting noses 42 and 43, will give a double oscillating action to shaft 32, during one revolution of main driving shaft 38, therefore shaft 32, with its double oscillating action, will give a double oscillating action to the feeding plate 56. The cam 61, with its single acting nose, will give a single oscillating action to shaft 35. Therefore shaft 35, with its single oscillating action, will, through mechanism described, drop the feed plate 56, below the surface of frame 1, thus causing an intermittent feed between the feed roller 8 and the feed plate 56.

The result obtained by this double action of the feed plate and the single action of dropping the plate is as follows. The feed plate, with its forward and backward and forward action, and in contact with feed roller 8, will feed the material forward and backward and forward again, the single acting cam then coming into operation and dropping the feed plate below the contact bearing between the material and the feed roll and the feed plate, will release the material. The feed plate 56, while in this position will then come back without feeding the material and again be brought into contact with roller 8 by means of the single acting cam. The double acting cam then coming into operation repeats the function above set forth.

The material to be burnished or finished is placed upon the feed plate 56 and adjacent thereto and between said feed plate and the feed roller 8, the edge to be burnished or finished extending into the slot 19 in the burnishing tool 18 and while the burnishing tool is oscillating forward and backward the feed plate and roller are holding the material in

alinement and the feed plate 56 is also oscillating forward and backward carrying the material with it; thus while the burnishing tool is working backward and forward the material is also being worked forward and backward and thus a double action is exerted upon the edge of the material being burnished; this action preventing any deteriorating or ill effect upon the material; this action being continuous and only interrupted when the feed plate 56 drops to begin refeeding. By using my invention delicate and easily marred surfaces can be acted upon and properly burnished without destroying or injuring them in any way. By reason of this peculiar reciprocating or oscillating action of the parts just described they are always in good working order and do not become gummed, stuck or clogged when certain kinds of material, which have a tendency to produce such results, are operated upon.

While I have described and shown certain specific mechanism for carrying out my invention, it will be readily seen that the same is capable of considerable modification and change without departing from the spirit and principle of my invention, and I wish to be understood as claiming that such modification and changes will still fall within the scope of my invention.

What I claim as new and my invention and desire to secure by Letters Patent is:

1. In a burnishing machine, a burnishing tool, means for moving the same forward and backward, a feeding plate, mechanism for operating the same forward and backward, means for dropping said feeding

plate at predetermined periods and feeding mechanism above the feeding plate operating in conjunction therewith.

2. In a burnishing machine, a burnishing tool, means for moving the same forward and backward, means for heating said burnishing tool, a feeding plate, mechanism for operating the same forward and backward, means for dropping said feeding plate at predetermined periods and feeding mechanism above the feeding plate operating in conjunction therewith.

3. In a burnishing machine, a burnishing tool, means for moving the same forward and backward, a feeding plate, mechanism for operating the same forward and backward, means for dropping said feeding plate at predetermined periods, and a feeding roller above said plate operating in conjunction therewith and capable of vertical adjustment.

4. In a burnishing machine, a burnishing tool, means for moving the same forward and backward, and feeding mechanism for carrying the material operated upon forward and backward and also feeding it forward, said burnishing tool and feeding mechanism operating simultaneously, the feeding action of the feeding mechanism being interrupted at predetermined periods during the operation of burnishing.

Executed at Cincinnati, Ohio, Nov. 30, 70
1915.

LOUIS J. VAN GUELLEN.
